DEVICE FOR DISTRIBUTING WOOD CHIPS IN PULP DIGESTERS

Application filed December 5, 1931. Serial No. 579,226.

This invention relates to the general art of paper making, and has reference more particularly to an improved mechanism for distributing wood chips in pulp digesters.

5 The general object of the invention is to provide an apparatus whereby the chips may be so distributed in the digester as to effect, in the first place, more uniform cooking conditions through a more uniform temperature 55 distribution within the digester, thereby improving the yield and quality of the pulp; and, in the second place, to secure a larger 60 charge of chips being introduced into the digester than is possible by the procedure 65 heretofore practiced by reason of a closer piling of the chips, thus considerably increasing the capacity of the cooking equipment.

In the present customary method of filling 20 digesters with chips, a spout is placed over the top nozzle of the digester, and the sliding gate in the chip bin bottom immediately 70 above the spout is opened. The chips fall by gravity through the spout and into the digester. As is the case with all materials 75 in small pieces, a cone-shaped pile is formed in the digester, the entering chips dropping on the apex and sliding down to a position of rest somewhere along the sides of the pile. The chips, having a slab-like form or shape, 80 tend to take a position of most stable equilibrium, which means that they will rest on one of the faces having the greatest surface area, rather than on one of the edges. They 85 slide down the cone in this position, with the result that a charge of chips is formed in the digester having a stratification corresponding to the angle of repose of the material. Not infrequently a stream of chips dropping 90 from the bin enters the top of the digester eccentrically, and this leads to a stratification apex line somewhat eccentric to the vertical center line of the digester. However, the angularity of the stratification still exists.

Considering now the effect of this peculiar 45 stratification upon the cooking process, after the digester is filled with chips and cooking liquor is introduced, the vessel is usually filled to the top with the re-agent and sealed by a top nozzle cover or cap, whereupon the heating 50 of the contents is begun. Two methods of

heating the contents are employed. That one which is almost universal in practice consists of introducing steam at sufficient pressure to overcome the back pressure of the contents into the bottom of the digester, either 55 through a bottom T or through nozzles spaced at regular intervals in one horizontal plane of the surface of the bottom cone. The steam is quickly condensed to water by the cooking liquor and gives up its latent heat, as well as 60 a portion of its sensible heat, to the latter. This warm liquor rises by convection through the digester contents, displacing colder liquor above, which falls to the bottom of the digester, is heated and, in turn, rises. Thus a 65 convection current of circulation develops in the liquor portion of the digester contents. As the contents warm up the vapor pressure 70 of the liquid, and also gas pressure of the dissolved sulphur dioxide in case of sulphite cooking liquor, causes a development of pressure in the digester. Further, the condensed steam increases the liquid content of the digester, causing it to fill up and develop a hydrostatic pressure, which is usually allowed 75 to reach a predetermined maximum and is then maintained at this point by relief of excess water vapor, sulphur dioxide gas and liquor through suitable outlets in the top nozzle. The relief of sulphur dioxide gas, in the sulphite process particularly, aids also in maintaining a circulation of the liquid content. The gas is released in the form of bubbles, and these rise through the digester, causing 80 upward motion of the liquid surrounding 85 them.

Now, the liquid must naturally flow in channels formed by the interstices between the chips. And if the chips have an angular stratification, such as results from the usual 90 method of filling, the channels or interstices must be somewhat continuous in the direction of the angular alignment or stratification. Since these channels lead upward and away 95 from the walls of the digester to its axis, the liquid stream in rising tends toward the axis or center of the digester, and in descending it follows the outside walls of the vessel because of the cooling effect resulting from radiation of heat from these walls. Hence, the 100

center of the digester contents is always found to be considerably hotter during the most of the cooking time than the outside portions, and the course of circulation can be followed very definitely by the temperature variations. While this condition is good from the standpoint of liquor circulation, it has an adverse effect upon the pulp quality and yield. It leads to non-uniformity in the product, inasmuch as part of the wood is exposed to the cooking-reagent at a higher temperature for a much longer time than other parts. Naturally, the cooking process is not completed until all the wood has been converted into pulp, and by the time the contents of the colder zones are completely converted, the contents of the warmer central zones will be considerably overcooked, resulting in a very appreciable yield and strength loss which, of course, is undesirable.

A more modern system of cooking involves the forced circulation of hot cooking liquor through the digester, accomplished by withdrawing the liquor from the top or bottom of the digester, passing it through a pump, and forcing it back into the digester at the bottom or top, as the case may be. This modification is less productive of zones of unequal temperatures in the digester, but its efficiency in this respect is not complete. The angular stratification of the chips causes most of the liquor to flow through the central zone of the digester if the liquor is forced in at the bottom, or along the walls if delivered at the top, and this leads to somewhat inactive zones in the digester contents which are not pulped as rapidly as the main body of the contents.

The present invention aims to eliminate the undesirable conditions in the digester outlined above, and employs, as the main feature of the invention, a novel device in the nature of an eccentric cone rotatably suspended in the digester slightly below the charging nozzle of the latter and disposed in the path of the falling stream of chips, for creating a substantially horizontal stratification of the chips in the digester and a closer packing of the same, by which a more uniform cooking and a considerable increase in the pulp obtained from each charge are secured.

The invention, its mode of operation, and the benefits and advantages inherent therein will all be readily understood and appreciated by persons familiar with this branch of the paper-making art from the following detailed description, taken in connection with the accompanying drawing, wherein I have illustrated one practical and simple form in which the invention may be embodied, and in which:

Fig. 1 is a partly diagrammatic view in vertical axial section of a pulp digester and its chip-distributing mechanism, illustrating the substantially horizontal stratification of

the charge obtained by the use of the present distributor.

Fig. 2 is a vertical section on an enlarged scale through the upper portion of the digester and its nozzle, showing the improved device for distributing the inflowing stream and effecting the horizontal stratification of the charge.

Fig. 3 is a further enlarged axial section of the anti-friction bearing member for the shaft of the cone distributor.

Fig. 4 is a top plan view of the cone distributor, in section through its shaft on the line 4—4 of Fig. 2.

Fig. 5 is an enlarged side elevation of the cone distributor and its shaft, partly broken out and in section, showing a countersunk bushing through which the cone is keyed to its shaft.

Referring to the drawing, 10 designates a digester of the usual form having a conical bottom portion 11 and a charging nozzle 12; and at 13 is indicated in Fig. 1 a pipe for steam or hot cooking liquor entering the lower end of the digester.

14 designates a sleeve of a size to have an easy sliding fit in the charging nozzle 12 and formed on its upper end with an annular flange 15 resting on the upper end of the nozzle. To the lower end of the inner wall of the sleeve 14 are attached, as by soldering, welding, or otherwise, equally spaced pairs of angle-attaching strips 16, between the inwardly projecting limbs of which are riveted or otherwise secured the outer ends of a plurality of downwardly and inwardly inclined flat spider arms 17 secured at their inner ends to a vertical bearing casing 18. In the upper and lower ends of the casing 18 are anti-friction bearings 19 and 20 of the ball type that are locked in place by upper and lower lock nuts 21 and 22. These lock nuts engage threaded portions 23 and 24 of a shaft section 25, which latter is formed with upper and lower annular shoulders 26 and 27 against which the inner rings of the bearings 19 and 20 are pressed by the lock nuts 21 and 22. These spaced anti-friction bearings afford a rigid and nearly frictionless lateral support for the rapidly rotating shaft 25; the construction permitting the filling of the space within the bearing casing 18 with a suitable lubricant (not shown) and the escape of the lubricant being guarded against by upper and lower glands 28 and 29 attached to the ends of the casing 18 by screws 30, and internally grooved to receive packing rings 31.

32 designates the main operating element of the chip distributor, this, in the embodiment of the invention herein shown, taking the form of an eccentric truncated cone. This cone member may be made of wood, metal or any other material well adapted to withstand the wear of contact with the falling

stream of chips impinging thereon and deflected thereby. As shown in Figs. 2 and 5, the lower portion of the shaft 25 extends some distance below the bearing 18, and the cone 5 32 is formed with an eccentric axial bore 33 that is fitted onto the lower end portion of the shaft 25 from below the latter. The cone 32 may, of course, be fixed on the shaft to rotate with the latter by any suitable or 10 desired means, but in Fig. 5 I have illustrated an attaching means well adapted to maintain the cone in rigid relation to the shaft under the considerable unbalance of the cone caused by its eccentric mounting when in 15 very rapid rotation. The lower end of the axial bore 33 is formed with a stepped countersink comprising a wide shallow portion 34 and a narrower deeper portion 35. Fitted within this countersink is a bushing comprising a body portion 36 filling the deeper countersink 35, and a head or flange portion 37 filling the shallow countersink 34. The bushing is locked on the shaft by an ordinary key 38 engaging registering keyways in the 20 shaft and bushing and the bushing is locked to the cone by screws 39 passed through the flange 37 and into the body of the cone. The lower end of the shaft 25 is preferably tapered, as shown, and the bore of the bushing 25 is correspondingly tapered to insure a tight fit and prevent any looseness or wobbling of the cone on the shaft due to wear. The lower end of the shaft is threaded to receive 30 a nut 40, by which, and the usual cotter pin 41, the cone and its bushing are securely locked on the shaft.

The cone and its shaft may be driven by any suitable drive extending through the 40 charging nozzle, but I have herein illustrated the use of a flexible drive shaft 42 extending axially through the sleeve 14 and suitably coupled to the upper end of the shaft 21 as by means of a knurled nut 43 secured to the 45 lower end of the flexible drive shaft 42. I may here state that after the digester has been filled with chips and before the contents are subjected to the digesting operation, it is, of course, necessary to remove from the 50 charging nozzle 12 the chip distributor and its supporting means. By providing a flexible drive shaft 42, the entire assembly can manifestly be withdrawn from the charging nozzle by simply lifting out supporting sleeve 14. In actual practice, the flexible shaft 42 is suspended from an overhead trolley carrying a motor and a drive from the motor to the shaft 42; but as these features 55 form no part of the present invention, I have not deemed it necessary to illustrate the same herein.

When loading the digester, the chips are directed into the upper end of the charging nozzle 12 through a suitable guide chute or 60 hopper; and the descending stream of chips

falling through the charging nozzle impinges upon the cone 32, which latter, during the charging operation, is rotated at a very high speed. The eccentricity of the cone causes the chips, when falling on it, to change their direction in a multiplicity of angles from a minimum, which is almost vertical, to a maximum, which is sufficiently inclined to direct the chips outwardly to the circumference of the digester; so that, so far as the downward sliding of the chips is concerned, the chips are deflected at widely varying angles to the axis of the digester. In addition to this sliding action of the chips, the cone also tends, by its rapid rotation, to throw the chips off tangentially. The combined result of this sliding action at varying angles and tangential impelling action is to scatter the chips with substantial uniformity throughout the entire cross section of the digester, so that the body of chips builds up in the digester with the substantially horizontal stratification indicated in Fig. 1, whereby the beneficial results of the invention, as hereinabove set forth, are secured.

I claim:

1. The combination with a pulp digester, of mechanism for distributing chips therein, comprising a conical member formed with a downwardly and outwardly tapered chip-deflecting surface presenting varying angles of inclination to its axis, means for rotatably mounting said conical member below the charging nozzle of the digester in the path of the falling stream of chips, and means for 95 rotating said conical member.

2. The combination with a pulp digester, of mechanism for distributing chips therein to create a substantially horizontal stratification of the chips in said digester, comprising a conical member of round cross-section formed with a chip-deflecting surface presenting progressively increasing angles of inclination to its axis from a minimum to a maximum, means for rotatably mounting 100 said conical member below the charging nozzle of the digester with its axis in line with the axis of said nozzle, and means for rotating said conical member.

3. The combination with a pulp digester, of mechanism for distributing chips therein, comprising a truncated eccentric cone, means for rotatably mounting said cone below the charging nozzle of the digester in the path 110 of the falling stream of chips, and means rotating said cone.

4. The combination with a pulp digester, of removable mechanism for distributing chips therein, comprising a sleeve slidably fitting within the charging nozzle of the digester and formed with a flange on its upper end resting on said nozzle, a vertical bearing member supported by said sleeve, a vertical shaft journaled in and extending below said bearing member, a truncated eccentric cone 125 130

mounted on the lower end of said shaft, and a drive shaft coupled to the upper end of said first-named shaft.

5. The combination with a pulp digester, of removable mechanism for distributing chips therein, comprising a sleeve slidably fitting within the charging nozzle of the digester and formed with a flange on its upper end resting on said nozzle, a vertical bearing member having arms attached to said sleeve, a vertical shaft journaled in and extending below said bearing member, a truncated eccentric cone formed with an axial bore mounted on the lower end of said shaft, said 10 bore having a countersink at its lower end, a flanged bushing filling said countersink and keyed to said shaft, means for attaching the flange of said bushing to said cone, and a drive shaft coupled to the upper end of said 15 20 first-named shaft.
